Primary Examiner — Susan Moon Lee(74) *Attorney, Agent, or Firm* — Morris Manning & Martin LLP; Tim Tingkang Xia, Esq.(57) **CLAIM**

The ornamental design for a memory module, as shown and described.

DESCRIPTION

FIG. 1 is a perspective view of a memory module showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines are directed to environment and are for illustrative purpose only; the broken lines form no part of the claimed design.

1 Claim, 4 Drawing Sheets(56)
